UNITED STATES PATENT OFFICE.

ALFRED SHEDLOCK, OF NEW YORK, N. Y., ASSIGNOR TO GUSTAVUS A. GOLDSMITH, OF SAME PLACE.

PAPER COLLAR.

SPECIFICATION forming part of Letters Patent No. 231,453, dated August 24, 1880.

Application filed March 8, 1880. (No model.)

To all whom it may concern:

Be it known that I, ALFRED SHEDLOCK, of New York, county and State of New York, have invented a certain new and useful Improvement in the Manufacture of Paper Collars, of which the following is a specification.

This invention relates to the manufacture of paper collars, and has for its object to overcome the objection to that class of collars manufactured from combined paper and cloth, which is folded over onto itself, so as to form a strip with cloth-covered edges of a width adapted for the cutting of two rows of collars therefrom on the interlocking plan, the cloth-covered edges of the strip forming the outside edges of the completed collars.

In this method of manufacturing collars, as shown in Letters Patent of the United States No. 217,937, granted to G. A. Goldsmith, July 20, 1879, the paper covered on one side with cloth is first cut into strips having parallel straight sides, then pasted and folded lengthwise with the two straight edges meeting in the center of the strip, which meeting of the edges appears in the laps or ends of the bands of the collars cut from the strip on the interlocking plan as a join on the face of the material, and are liable to open and break away upon using the collars. I overcome this objection by first cutting the stock into strips having parallel sinuous edges of such a conformation which, when folded over and pasted, meet on the body of the strip in a sinuous joint which corresponds to and is in the position of the longitudinal interlocking edges of the two rows of collars as cut from the strip, thus enabling collars having both sides covered with cloth and perfectly smooth and uniform to be cut without any waste of material; 40 and in the better form of collars, which are the principal ones made from this class of stock, and which are so shaped as to necessitate a little waste from the center of the strip, this sinuous join is in the center of the waste, 45 as will be fully hereinafter described by reference to the accompanying drawings, forming part of this specification, in which—

Figure 1 represents a strip of collar-stock with sinuous parallel edges. Fig. 2 represents 50 the manner in which collars are cut from the

folded stock, leaving a little longitudinal waste between the two rows of collars; and Fig. 3 represents the strip folded and pasted, showing by dotted lines the manner collars are cut therefrom without any longitudinal 55 waste.

The collar-stock, composed of paper covered on one side with linen, is made about one yard wide and any desired length. It is first cut into strips with sinuous parallel edges, as represented in Fig. 1, which strips are first pasted and then folded on the dotted lines *a a*, the sinuous edges meeting in the center of the folded strip, as shown in Figs. 2 and 3. The form of the sinuous edges is such as to correspond to the longitudinal division-line of collars cut on the interlocking plan.

The dotted lines *b b* in Fig. 3 represent the form of the ends of turn-down collars as they are cut from the strip, the interlocking longitudinal edges of the two rows of collars meeting on the sinuous joint *c* of the edges of the folded strip.

In cutting collars from the strip in this manner it will be observed that no waste of 75 material occurs between the longitudinal edges of the collars, the only waste being from the button-holes and the small pieces marked *b²* *b²*, which form the ends of the bands and the parts of the ends which are folded under in 80 the perfected collar.

The dotted lines *d d*, Fig. 2, represent stand-up collars, the conformation of the bands of which to enable them to set perfectly on the neck of the wearer is such as necessitates some 85 waste of material occurring between the longitudinal edges of the two rows of collars. The sinuous joint *c* of the folded strip in this case is, as shown, located along the middle of the longitudinal waste.

It is obvious that the sinuous edges of the strips of linen-covered material or of strips having one side otherwise finished may be made to conform to any shape of collar cut from the folded strip on the true interlocking 95 plan, as shown at Fig. 3, or approximately to the edges of any shape collars which do not perfectly interlock, as shown at Fig. 2, and that by this method of manufacturing collars having both sides and the outside edges cov- 100

ered with linen, or the finished side of the material, may be made with the whole of the surfaces of the two sides perfectly uniform and without seams thereon.

5 I hereby disclaim anything shown or described in the before-mentioned Letters Patent to G. A. Goldsmith, No. 217,937, dated July 29, 1879; but

What I do claim, and desire to secure by

10 Letters Patent, is—

1. The improved method of manufacturing collars, consisting in forming the material into strips with sinuous parallel edges, pasting and folding the strip so that the edges meet 15 to form a sinuous joint which approximately

or exactly corresponds with the longitudinal interlocking edges of the two rows of collar to be cut therefrom, substantially as and for the purposes hereinbefore set forth.

2. As a new article of manufacture, a collar 20 cut from a folded strip and having both of its surfaces perfectly uniform and without any seams, substantially in the manner hereinbefore set forth.

In testimony whereof I have hereunto set 25 my hand this 5th day of March, A. D. 1880.

ALFRED SHEDLOCK.
